UNITED STATES PATENT OFFICE.

JANNETTE MILLER, OF EAU CLAIRE, WISCONSIN.

ICE RETAINER.

Application filed September 11, 1922. Serial No. 587,544.

To all whom it may concern:

Be it known that I, JANNETTE MILLER, a citizen of the United States, residing at Eau Claire, in the county of Eau Claire and 5 State of Wisconsin, have invented certain new and useful Improvements in Ice Retainers, of which the following is a specification.

The present invention relates to an ice 10 retainer for pitchers or other vessels used as containers for water or other liquids in which a large piece of ice or large pieces of ice or cracked ices are put in the liquid for the purpose of cooling and which liquid 15 is to be poured from such pitchers or other vessels so as to prevent such liquids splashing on the table or other places where such liquids may be poured and to retain the ice in such pitchers or other vessels and yet 20 not prevent the easy and uninterrupted flow of such water or other liquids.

The further object of this invention is to construct a cheap, light, open, twisted or other pliable wire mesh with openings sufficiently 25 large as not to prevent the easy and uninterrupted flow of the water or other liquids contained in the pitchers or other vessels and still to prevent the flow of any pieces of ice sufficiently large to cause a 30 splashing so as to wet or moisten in any degree the table or other places where said water or other liquids may be poured.

For the purpose of illustrating the general idea of the invention, the invention will 35 be described in detail, although it is understood that any modification and changes can be made in the details of constructions including the materials used without departing from the spirit of the invention 40 and the scope of the claims.

For a full understanding of the invention reference is to be had to the following description and accompanying drawing in which,—

45 Figure 1 is a top plan view of an ice retaining device constructed in accordance with the invention.

Figure 2 is a side elevation thereof, showing it as applied to a pitcher, the upper portion 50 of the pitcher being indicated by dot and dash lines.

Figure 3 is a detail view illustrating an extension wire which can be used when the encircling wire is not long enough to reach 55 around the pitcher.

Figure 4 is a detail view of the adjustable

and detachable connection between the ends of the encircling wire.

The reference character A designates the upper portion of a pitcher which is provided with the usual pouring mouth B. The ice retaining device is formed of strands of suitable material, such as wire, and includes a strand D which is adapted to encircle the pitcher or other container at a point toward the upper end thereof. One end of the wire D terminates in a loop F, and the other end of the wire D is adapted to be inserted through the loop and bent to interlock with the same, as indicated in Figure 4, after 70 the wire has been drawn around the body of the pitcher.

An arched wire E extends transversely across the top of the pitcher or container A and has the two ends thereof secured to the encircling wire D. An ice retaining mesh C connects the arched wire E and the encircling wire D and extends around the pouring mouth B of the pitcher, so that it will retain pieces of ice or other solid 80 pieces within the pitcher without interfering with the pouring of the liquid contents of the pitcher through the pouring spout B in the usual manner.

In applying the ice retainer to a pitcher the encircling wire D is drawn taut around the body portion of the pitcher, and in the event the wire should not be sufficiently long for this purpose an extension wire I, such as that shown in Figure 3, can be utilized. The wire I has a hooked end that can be engaged with the loop F, and the extension wire can then be connected to the other end of the encircling wire in such a manner as to hold the encircling wire taut 90 around the pitcher and keep the ice retaining mesh C in proper position over the pouring spout of the pitcher.

Thus describing my invention what I claim as new and desire to secure by Letters Patent is,—

1. An ice retainer for pitchers and like containers, including an encircling strand adapted to encircle the exterior of the pitcher, an arched strand extending transversely across the pitcher and having the ends thereof connected to the encircling strand, and an ice retaining mesh extending around the pouring mouth of the pitcher and connecting the arched strand and the 105 encircling strand.

2. An ice retainer for pitchers and like

containers, said retainer being formed of wire and including an encircling wire adapted to be drawn taut around the exterior of the pitcher and having an adjustable connection between the ends of the wire, an arched wire extending transversely across the top of the pitcher and having the ends thereof connected to the encircling wire, and a plurality of wires connecting the encircling wire and the arched wire and intersecting each other at an angle to form an ice retaining mesh which extends over the pouring mouth of the pitcher.

3. An ice retainer for pitchers and like containers, including an encircling wire adapted to extend around the exterior of the

pitcher, a separate extension wire having a detachable interlocking connection with one end of the encircling wire and adjustably engaging the other end of the encircling wire to enable the encircling wire to be drawn taut around the pitcher, an arched wire extending across the top of the pitcher and connected to the encircling wire, and an ice retaining mesh connecting the arched wire and the encircling wire and extending across the pouring mouth of the pitcher.

In witness whereof I have hereunto affixed my signature this 1st day of August, 1922.

JANNETTE MILLER.
